UNITED STATES PATENT OFFICE

EDGAR A. GILLINDER, OF PHILADELPHIA, PENNSYLVANIA

LIGHTING FIXTURE

Application filed December 21, 1928. Serial No. 327,501.

My invention relates to a novel construction of semi-indirect electric lighting fixture, wherein I have provided an upper fixed closure of conical shape having on its outer 5 surface a series of novel light reflecting prisms arranged in annular rows with the sizes of said prisms decreasing from the base of said conical closure to its apex, said upper conical member serving as a closure 10 for the bowl or lower portion of the fixture, which latter is adjustably mounted with respect to said fixed upper member so that upon removal of a lower readily accessible locking nut, the lower portion of the fixture 15 can be readily lowered, so as to give access to the interior for the purpose of replacing electric light bulbs, inspection, cleaning or repairs.

My invention further consists of a novel 20 construction of an upper conical light reflecting member provided with prisms of a novel construction arranged in annular rows wherein the apices or high points of an annular series of prisms merge into the low 25 points of the next aligning prisms of the next annular series, the area of each row of prisms decreasing upwardly whereby the light is softened, diffused and evenly deflected upwardly.

It further consists of novel means for supporting and adjusting the lower shade portion of the fixture.

It further consists of other novel features 35 of construction and advantage, all as will be hereinafter set forth in the specification and claims appended hereto.

For the purpose of illustrating my invention I have shown in the accompanying 40 drawings several forms thereof which are at present preferred by me, since the same have been found in practice to give satisfactory and reliable results, although it is to be understood that the various instrumentalities 45 of which my invention consists can be variously arranged and organized and that my invention is not limited to the precise arrangement and organization of the instrumentalities as herein shown and described.

Figure 1 represents a side elevation of a

novel lighting fixture, embodying my invention.

Figure 2 represents on an enlarged scale, a front elevation of a portion of the upper 55 fixed prism member seen in Figure 1.

Figure 3 represents a sectional view on the line 3—3 of Fig. 2.

Figure 4 represents a section on line 4—4, Fig. 2.

Figure 5 represents a section on line 5—5, 60 Fig. 2.

Figure 6 represents on an enlarged scale a vertical sectional view on line 6—6, Fig. 1.

Figure 7 represents on an enlarged scale, 65 a sectional view of the lower portion of the fastening means seen in Fig. 6.

Figure 8 represents a transverse section on line 8—8, Fig. 6.

Similar numerals of reference indicate 70 corresponding parts in the figures. Referring to the drawings:

1 designates my novel construction of a semi-indirect lighting fixture which comprises the upper conical fixed member 2 of clear glass, and the lower shade or globular member 3 of opal glass, the latter being provided with the annular seat 4 in its upper portion in which the bottom peripheral edge 75 of the fixed upper member 2 is seated.

The electric lights 6 seen in Fig. 6 can be 80 supported within the fixture in any suitable manner, one form being shown in Fig. 6, wherein 7 designates a supporting eye, below which is the head 8, which rests on the conical cap member 9 which forms a closure and 85 finish for the top of the fixture.

10 designates a socket block positioned 90 in the upper portion of the fixed prism member 2 and having the lamp sockets 11 secured thereto by any suitable means. 12 designates a tube or piece of pipe which passes through the socket block 10 and the upper fiber or asbestos washer 13, and thence through the members 9 and 8. The parts 7 and 9 may be 95 integral and the upper end of the tube 12 may be screw threaded into the parts 13 and 8, the socket block 10 and its adjuncts being securely held in assembled position by the nut 14. The conductors 15 lead through the 100

top of the tube 12 and the passages 16 to the light sockets 11.

17 designates an outer sleeve slidably mounted or telescoping upon the lower end of the tube 12, which latter is provided with the longitudinal slots 18, seen in Figures 6 and 8, through which pass the transverse bolt 19, which is fixedly secured to the sleeve 17, whose lower end passes through the shade 3 and is secured thereto so that said sleeve and shade can be raised and lowered as a unit. When the parts are in assembled position as seen in Figs. 6 and 7, the lower end 20 of the tube 12 projects below the lower end 21 of the sleeve 17 and is exteriorly threaded for engagement with the nut 22. The shade 3 is secured to the sleeve 17 by the upper nut 23 and fibre washer 24, and by the lower nut 25, the member 26 which may be of sheet metal or hard rubber, and the rubber packing disk 27.

The nut 25 may be round and knurled as seen in Fig. 1.

The parts 24 and 27 can be of any resilient, cushioning or fibrous material if desired. The member 26 being of thin sheet metal or hard rubber will yield slightly when the nut 25 is tightened so that the requisite tight joint will be formed between the sleeve 17 and the shade 3. The parts in assembled position will appear as in Fig. 6. When it is desired to have access to the interior of the fixture, it is only necessary to remove the nut 22 seen in Figs. 6 and 7, whereupon the shade 3 and its adjuncts can be lowered into the position seen in dotted lines in Fig. 6, the contact of the bolt 19 with the lower ends of the slots 18, as seen dotted in Fig. 6 arresting the downward movement of the shade, as is evident. When the shade is in the position seen dotted in Fig. 6, the lights can be inspected, cleaned and replaced and the whole interior of the fixture is readily accessible. Upon raising the shade, its sleeve 17 and their adjuncts, and replacing the nut 22, the parts will appear as seen in Fig. 6. The outer surface of the upper fixed portion 2 of the fixture is provided with annular rows of prisms, five in the present instance, which are designated 28, 29, 30, 31 and 32, as will be understood from Figs. 1 and 2, the prisms in each successive row decreasing in size upwardly, the larger prisms being in the series designated 28. This novel arrangement of prisms consists in having the low point of a pair of the lower prisms 28 as 33 (see Figs. 2 and 3) merge into the high point or apex 34 of the aligning prism above it. The high point or apex 34 of each prism in the row 29 merges into the aligning low point 35 between a pair of prisms in the row 30. The low point 35 just referred to merges into the high point or apex 36 of the aligning prism in the row 31. The high point 36 (seen in Fig. 2) merges into the aligning low point

37 between a pair of prisms in the upper row 32.

The foregoing description applies to each row of prisms considered in vertical alignment as seen in Figs. 2 to 5, and my novel construction not only affords an upper closure for a semi-indirect lighting fixture, but in addition greatly augments, softens, and diffuses the light over prior constructions, where the top of the fixture has been left open.

It will be understood that if desired the prisms may be omitted from the upper conical member 2, and while I have described the latter as being composed of clear glass, and the lower shade portion 3 of opal glass, any other desired glass may be employed.

It has heretofore been customary in fixtures of this general character to leave the top open which affords ingress to dust and dirt which settles in the shade portion 3. By my novel construction, I not only close the top of the fixture, but in addition employ novel means for enhancing and augmenting the upwardly reflected light, as is evident.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention, what I claim as new, and desire to secure by Letters Patent, is:

1. In a lighting fixture, a fixed conical glass member, a tubular rod penetrating the apex of said glass member, the top of said tubular member being screw threaded, a metallic cap fitted to the apex of said glass member, an electric socket holding member having engagement with said tubular rod, a resilient member interposed between said socket holding member and the apex of said glass member, and means for clamping said metallic member, glass member, resilient member, and socket holding member together.

2. In a lighting fixture, an upper fixed conical closure of glass, a lower bowl of glass which is movable with respect to the fixed closure and provided with an upper peripheral seat for the outer periphery of said upper closure, an inner tubular member carried by said fixed closure and having its upper end seated on the apex of said fixed closure, an outer lower tubular member receiving and having telescopic relation with the first mentioned tubular member, said bowl being carried by the lower of said members, and means engaging said inner tubular member for clamping said bowl in elevated position.

3. In a lighting fixture, an upper fixed

conical closure of glass, a lower bowl of glass which is movable with respect to the fixed closure, an inner tubular member carried by the apex of said fixed closure and extended through said bowl, an outer lower tubular member having telescopic relation with the first mentioned tubular member, said bowl being carried by the outer of said members, means including a slot in said inner member and a pin connection carried by said outer member for guiding said telescopic parts, and means on said inner member for clamping said bowl in elevated position.

4. In a lighting fixture, an upper fixed conical closure of glass, a lower bowl of glass which is movable with respect to the fixed closure, an inner tubular member carried by said fixed closure and extending through said bowl, an outer lower tubular member having telescopic relation with the first mentioned tubular member, said bowl being carried by the lower of said members, means including a slot in said inner member and a transverse pin connection in said outer member for guiding said telescopic parts, resilient means acting as washers arranged between the inner and outer surface of said bowl, means for securing said bowl to said outer tubular member, and means for clamping said bowl in elevated position.

5. In a lighting fixture the combination of an upper fixed closure, a lower shade member having a seat in its upper portion for the lower edge of said upper closure, a tube secured to said upper closure and passing through said shade member, said tube being slotted in its lower portion, a sleeve secured to said lower shade member and telescopically mounted upon said tube, and a nut on the lower end of said tube for holding said upper closure and lower shade member in assembled position.

6. In a lighting fixture, an upper fixed conical closure of clear glass, a lower bowl of opal glass movably supported with respect to said upper fixed closure, an inner tube having its upper end passing through the apex of said upper closure, an upper cap member engaging the upper end of said tube, said inner tube being extended through said bowl, an outer lower tube of larger diameter than said inner tube and telescopically receiving the latter, means for securing said bowl to said outer tube, means for guiding said telescopic tubes and arresting the descent of said bowl, comprising slots in said inner tube, and a transverse pin engaging said outer tube, and slidable in said slots, and clamping devices on the lower end of said inner tube for retaining said upper and lower glass members in assembled position.

7. In a lighting fixture, an upper fixed conical closure of clear glass, a lower bowl of opal glass movably supported with respect to said upper fixed closure, an inner tube hav-

ing its upper end passing through the apex of said upper closure, an upper cap member engaging the upper end of said tube and provided with an eye, said upper tube being extended through said bowl, an outer lower tube of larger diameter than said upper tube telescopically receiving the latter, means for securing said bowl to said outer tube, means for guiding said telescopic tubes and arresting the descent of said bowl, comprising slots in said inner tube, a transverse pin engaging said outer tube and slidable in said slots, clamping devices on the lower end of said inner tube for retaining said upper and lower glass members in assembled position, and a seat in the peripheral upper edge of said lower bowl for the reception of the lower peripheral edge of said upper fixed closure.

8. In a lighting fixture, an upper fixed conical closure of clear glass, closed at its apex and having its outer surface provided with a series of reflecting prisms, arranged in annular rows, the sizes of said prisms decreasing from the base of said closure to its apex, a lower bowl of opal glass movably supported with respect to said upper fixed closure, an inner tube having its upper end passing through the apex of said upper closure, an upper cap member engaging the upper end of said tube and provided with an eye, said upper tube being extended through said bowl, an outer lower tube of larger diameter than said upper tube telescopically receiving the latter, means for securing said bowl to said outer tube, means for guiding said telescopic tubes and arresting the descent of said bowl, comprising slots in said inner tube, a transverse pin engaging said outer tube and slidable in said slots, clamping devices on the lower end of said inner tube for retaining said upper and lower glass members in assembled position, and a slot in the peripheral upper edge of said lower bowl for the reception of the lower peripheral edge of said upper fixed closure.
